CLAIM

The ornamental design for a bag as shown and described.

DESCRIPTION

FIG. 1 is a front left perspective view of a bag showing our design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

FIGS. 1-7 include broken lines that are included for the purpose of illustrating portions of the bag that form no part of the claimed design.

1 Claim, 7 Drawing Sheets
